UNITED STATES PATENT OFFICE.

CLARENCE H. BENNETT, OF JAMESBURG, NEW JERSEY, ASSIGNOR, BY MESNE ASSIGNMENTS, TO BEN-WAT CORPORATION, OF NEW YORK, N. Y., A CORPORATION OF NEW JERSEY.

MIXER.

Application filed April 29, 1919, Serial No. 293,426. Renewed April 23, 1925.

To all whom it may concern:

Be it known that I, CLARENCE H. BENNETT, a citizen of the United States, and a resident of Jamesburg, in the county of Middlesex and State of New Jersey, have invented a new and Improved Mixer, of which the following is a full, clear, and exact description.

The object of the invention is this provision of construction which shall subdivide an explosive mixture into minute particles subsequent to its leaving the atomizer of the carburetor, together with additional means which shall even further divide the particles, to insure of a high combustible mixture in which the explosive medium is evenly distributed.

With these objects in view, reference is had to the attached sheets of drawings which illustrate one practical embodiment of my invention, and in which—

Figure 1 is a sectional side view through my carburetor;

Fig. 2 is a section taken along the line 2—2 of Fig. 1; and

Fig. 3 is an enlarged side elevation of certain details along the line 3—3 of Fig. 1, with part of such details of construction broken away.

In these various views, like reference numerals designate similar parts, and the reference numeral 1 indicates a casing open at the ends. One of these ends is closed by means of a housing 2, as indicated at 3. The housing 2 may include a ring-shaped part 4, a cap portion 5, and an air inlet, as indicated by the reference numeral 6.

Extending inwardly from the inner edge of the ring-shaped portion 4, and preferably integral therewith, is a tubular member 7, which is provided with an outwardly-extending flange 8 around its upper edge, for a purpose hereinafter more fully specified. The ring 4 has openings, such as 9, broken through at the portion between the tube 7 and a point intermediate to the inner face of the cylindrical casing 1. Closing such openings is a ring 10 forming a slideable valve, which seats against the under face of the ring 4 and is of such diameter as to completely close the openings 9 and to be slideable along the tubular member 7. Any convenient means, such as a spring 11, is interposed between the inner face of the ring 10 and a shoulder, such as 12, preferably in-

tegral with the tubular member 7 and extending from its outer face.

Extending through the casing and communicating with the atmosphere is an air tube 13 which projects through the tubular member 7 and terminates at a point centrally of such tubular member. A hollow pear-shaped casing, such as 14, is fixed to the innermost end of the tube 13; and communicating with the interior of this pear-shaped casing, and extending to a point in the same plane with the tube 13, is a nozzle 15 which has connected to it a pipe 16 adapted to permit a flow of gasoline into the nozzle 15, such flow being regulated by means of any convenient valve, such as a needle valve 17.

The smaller end of the pear-shaped casing 14 is open, and such opening is formed with tapered sides, as indicated by the reference numeral 18, so as to form what might be termed a "valve seat" for a valve, which includes a pointed set screw mounted through the apex of a yoke 20 which terminates in a base 21 acting as a valve for opening 22 formed in a cap 23 serving to close the end of the tubular member 7. A valve stem 24 projects through the cap 23 and extends through the cap portion 5 of the housing 2. The valve 21 is normally held seated by means of an adjustable tension provided, for instance, by a coil spring 25 encircling the valve stem 24 and extending between the cap 5 and a nut 26 mounted upon the end of the valve stem 24 by means of screw threads 90 which may be provided, such as 27.

Mounted above the annular flange 8, and extending above the same, are a series of ring-shaped plates 28 which are secured to such flange by any convenient means, such as bolts 29. As illustrated in Fig. 1, these plates are held in spaced relationship by any suitable means. Closing the uppermost end of the tubular member 7 is a disk 30 upon which are mounted wires 31 extending downwardly and adjacent the inner edges of the plates 28, and having their lowermost ends free to vibrate.

A manifold 32 conducts the combustible mixture to the point at which it is to be used, and a conventional throttle valve 33 is provided which may regulate the flow of such mixture. Extending from the manifold 32, and, if desired, integral therewith, is a plate 34 which serves to close the upper

end of the casing 1. Mounted upon this plate are bolts 35, spaced ring-shaped plates 36, a disk 37, and upwardly-extending wires 38 mounted upon such disk, corresponding in every particular to the bolts 29, ring-shaped plates 28, disk 30, and wires 31.

In operation it will now be seen that the fuel will enter the carburetor by means of a pipe, such as 16, and, by virtue of the suction created by the engine while running, the fuel will be atomized by means of the inrush of air through the tube 13 at a point slightly above the nozzle 15. The mixture thus resulting would be comparatively rich and unsuitable for efficient running conditions; and I have provided, by means of the valve 21, an additional air inlet which will serve to provide a suitable mixture within the tubular member 7, it being understood that the valve 21 will open proportionately to the speed of the engine, and that the opening of such valve will proportionately open the valve, including the set screw 19, and the open end 18 of the pear-shaped member 14. The combustible mixture will now strike the wires 31, and these wires will be vibrating to quite an extent, particularly by virtue of their upper ends being fixedly secured and their lower ends being free. After having passed the wires 31, and having its particles minutely subdivided, the combustible mixture is further broken up by passing through the closely-spaced plates 28; and, as indicated by the arrows, the mixture will now enter the casing 1. Should the engine be running at a fairly high rate of speed, the suction created thereby will be so great that the tube 13 and the valve 21 might not be able to conduct the passage of sufficient air, which objection is overcome by the provision of the valve 10, which will permit the influx of additional air into the casing 1, which air will comingle with the combustible mixture at a point between the flange 8 and plate 30. The mixture will now pass through the plates 36 and pass the vibrating wires 38, insuring the proper mixing action of the fuel with the additional air supply by means of the valve 10, and the completed mixture will now pass the throttle valve 33 and into the manifold 32.

It will be noted that quite independent of the vaporization of the mixture and the introduction of additional air thereinto, that the baffling means comprising the two spaced plate units will affect the mixture in such a manner as to insure an intimate co-mingling of the particles thereof. Thus as in Figure 1, the mixture will flow freely through the tube 7 at a speed corresponding substantially to the speed of the fluid flow within the intake manifold (the diameter of the tube and manifold being substantially equal). In flowing through the first baf-

fling means the fluid mixture will have its flow retarded, incident to the fact that the casing 1 is of a far greater diameter than the tube 7. Thus although the particles of the mixture will be broken up, incident to the action of the fuel between the vibratory members and the plates 28, it will be understood that the heavier particles of the same, i. e., the drops of fuel which are not readily digested will not continue with the mixture flow, in that the same is not moving with anything like the speed of the mixture within the tube 7. Thus, although the vaporized particles of the mixture are broken up in the passage through the first baffling means and a better explosive quality is accordingly incorporated in the mixture, the heavier drops of fuel will not continue toward the intake manifold. The mixture will now flow upwardly through the casing and in order to enter the intake manifold, it must necessarily pass around plates 36 and the wires 31 and in its passage through the second baffling means consisting of these members it is obvious that the rate of flow will be materially increased so that the particles of the mixture are so evenly distributed and minutely sub-divided so as to form an explosive fluid in the nature of a vapor, it being obvious that a mixture of this type will be of the best possible quality for the purpose intended.

I wish it understood that I do not desire to be limited to the particular arrangement illustrated, and that the construction of the various valves might readily be changed at will, and that a single set of ring-shaped plates and vibrating wires might be utilized. Also, a set of such plates and wires might be used in connection with any type of carburetor now on the market and would produce a finished mixture which would be far more efficient in operation, as well as more economical, than the operation of the carburetor alone.

Having now described my invention, what I desire to claim is:

1. A mixer including a casing formed with inlet and outlet openings, a series of spaced plates arranged around the inlet opening of said casing, said plates being formed with openings aligning with and forming a continuation of the inlet opening of said casing, a solid plate secured to and arranged beyond the outermost of said first named plates, and a similar series of plates arranged around said outlet opening whereby said mixture will enter through the inlet opening of said casing, pass outwardly between the first named plates beyond the edges of the same, and inwardly through the second series of plates.

2. A mixer including a plurality of plates each formed with an opening, and arranged in spaced relationship to each other, said

openings being substantially in alignment, a solid plate arranged beyond and secured to the outermost of said first named plates, and a series of vibratory members secured 5 to said last named plate and extending adjacent the inner edges of said first named plates.

3. A mixer including a plurality of plates each formed with an opening and arranged 10 in spaced relationship to each other, said openings being substantially in alignment, a solid plate arranged beyond and secured to the outermost of said first named plates, and a series of wires having one of their ends 15 secured to said plate, their bodies extending adjacent the inner edges of the opening forming a part of said first named plates and being free to vibrate.

4. A mixer including a casing formed 20 with inlet and outlet openings, a baffling means fixed within said casing and disposed adjacent said inlet opening, a chamber affording a relatively large space into which the gases pass from said baffling means and 25 a second baffling means also fixed within said casing and adjacent the outlet opening, said baffling means affording a passage from

said relatively large space to the outlet whereby the flow of fluid is first retarded in passing through the first baffling means 30 and is then accelerated in its passage through the second baffling means to the outlet.

5. A mixer including a casing formed with inlet and outlet openings, a mixture 35 baffling means adjacent one of said openings, a disk forming a part of said baffling means and a plurality of vibratory members having one of their ends secured to said disk, their opposite ends extending toward 40 said opening and being free to vibrate.

6. A mixer including a casing formed with inlet and outlet openings, a baffling means disposed adjacent to each of said openings, a disk forming a part of each of 45 said baffling means and being disposed at the outermost ends of the same and a plurality of wires for each of said baffling means, said wires having one of their ends attached to each one of said disks, their 50 opposite ends extending inwardly toward one of the casing openings and being free to vibrate.

CLARENCE H. BENNETT.
